UNITED STATES PATENT OFFICE.

MAX TONNEMANN, OF BROOKLYN, NEW YORK.

DESIGN FOR A SOUVENIR-PLATE.

SPECIFICATION forming part of Design No. 34,958, dated August 20, 1901.

Application filed July 27, 1901. Serial No. 69,993. Term of patent 14 years.

To all whom it may concern:

Be it known that I, MAX TONNEMANN, a citizen of the Empire of Germany, residing in New York, borough of Brooklyn, in the State 5 of New York, have invented and produced a new and original Design for Souvenir-Plates, of which the following is a specification.

This invention relates to designs for souvenir-plates.

10 The accompanying drawing shows a front elevation of my new design.

As shown in the drawing, the leading or material feature of my design consists of a center disk *a*, having a circumferential rim *a'* and radial handles *b* extending therefrom. 15 Intermediate the handles are circular rings *d* in the nature of life-preservers, said rings be-

ing connected by ropes *e*. Above the center disk *a* is arranged a cross-bar of an anchor *f*, with an eye *g*, and below the disk the lower 20 part or flukes of an anchor, the lower part of the anchor being provided with a few links *g'*.

I claim as new and desire to secure by Letters Patent—

The design for a souvenir-plate, as herein 25 shown and described.

In testimony that I claim the foregoing as my invention I have signed my name in presence of two subscribing witnesses.

MAX TONNEMANN.
